UNITED STATES PATENT OFFICE.

JOHN R. WILSON, OF McDOWELL, WEST VIRGINIA.

HARNESS ATTACHMENT.

SPECIFICATION forming part of Letters Patent No. 760,506, dated May 24, 1904.

Application filed January 10, 1903. Serial No. 138,549. (No model.)

To all whom it may concern:

Be it known that I, JOHN R. WILSON, a citizen of the United States, residing at McDowell, in the county of McDowell and State of West Virginia, have invented a new and useful Harness Attachment, of which the following is a specification.

This invention is an attachment to be used in connection with a set of harness for the purpose of preventing the harness being rapidly worn out by contacting with rough surfaces.

In coal-mines it is practical to haul the coal-cars by mules, and the harness frequently comes in contact with the roof of the mine, and consequently is rapidly worn, and it is with the idea of avoiding this rapid wearing of the harness that the present attachment has been designed; and with this object in view the invention consists, essentially, of a leather pad adapted to be arranged above the ordinary harness-saddle, said pad having straps connected therewith, said straps being connected to the leather pad by means of metal clips, which metal clips come in contact with the roughened surface, and thereby prevent the leather portions of the harness and attachment being worn.

The invention consists also in certain details of construction hereinafter fully described, and pointed out in the claim.

In the drawings forming part of this specification, Figure 1 is a perspective view of a harness attachment constructed in accordance with my invention. Fig. 2 is a top plan view of the pad, together with the metal fastening devices for connecting the straps thereto; and Figs. 3 and 4 show details of construction.

In constructing a harness attachment in accordance with my invention I employ a leather pad A, which is adapted to be arranged upon the ordinary harness-saddle and is of such

size and shape as to completely cover the same. This pad A has a metal strap B, secured centrally to the top thereof, said strap being bent back upon itself, as shown at B', for the purpose of connecting the links C to the top of the pad, the ends of the strap being brought close together and securely riveted to the pad by means of rivets B''. Front straps D are connected to the links C by means of metallic clip-plates E, and the rear straps F are connected to said links by means of the metallic clip-plates G, and girth-straps H are connected to said links by means of the clip-plates I, said clip-plates being securely fastened to the ends of the straps by means of rivets K. The free ends of the straps are also provided with buckles or any other suitable means for connecting them to the harness proper.

It will thus be seen that I provide a simple attachment which is arranged directly upon the ordinary harness and will protect said harness from coming in contact with the top of the mine, and inasmuch as those portions of the attachment which come in contact with the mine are metal it is obvious that this attachment will greatly prolong the life of an ordinary set of harness used in a mine.

Having thus fully described my invention, what I claim as new, and desire to secure by Letters Patent, is—

A device of the kind described comprising an elongated, flat, leather pad, rectangular links, a metal strap bent upon itself and connecting said links, said strap being secured midway the links to the longitudinal center of the pad, and a plurality of securing-straps connected to each link.

JOHN R. WILSON.
